UNITED STATES PATENT OFFICE.

JOHN GIBSON, OF NOROTON HEIGHTS, CONNECTICUT.

DISCHARGE-CHUTE FOR COAL CARTS OR WAGONS.

SPECIFICATION forming part of Letters Patent No. 769,898, dated September 13, 1904.

Application filed March 19, 1904. Serial No. 198,838. (No model.)

To all whom it may concern:

Be it known that I, JOHN GIBSON, a citizen of the United States, residing at Noroton Heights, in the county of Fairfield and State 5 of Connecticut, have invented certain new and useful Improvements in Discharge-Chutes for Coal Carts or Wagons, of which the following is a specification, such as will enable those skilled in the art to which it appertains to 10 make and use the same.

This invention relates to coal carts and wagons; and the object thereof is to provide improved means for discharging the coal from vehicles of this class; and with this and other 15 objects in view the invention consists in the construction, combination, and arrangement of parts herein described and claimed.

The invention is fully disclosed in the following specification, of which the accompanying drawings form a part, in which the separate parts of my improvement are designated by suitable reference characters in each of the views, and in which—

Figure 1 is a rear end view of a coal cart 25 or wagon provided with my improvement and showing the method of its operation; Fig. 2, a similar view, partly in section and on an enlarged scale; Fig. 3, a section on the line 3 3 of Fig. 2, and Fig. 4 a plan view of a detail 30 of the construction.

In the drawings forming part of this specification I have shown at α an ordinary coal cart or wagon provided with the usual body or bed α^2 , which is supported on axles α^3 , only 35 the rear axle being shown, and in practice the bed or body α^2 is connected with the axles by upright supports α^4 or in any desired manner, all these parts being of the usual construction.

Secured to the bottom portion of the bed 40 or body α , at the rear end thereof, is a transverse hanger b , composed of ordinary T-iron in the form of construction shown, and resting on the hanger b and running longitudinally of the cart or wagon body and beneath 45 the same and parallel therewith is a supplemental support b^2 , consisting of an I-beam or similar device, and mounted on the supplemental support b^2 and movable longitudinally thereof is a slide c , provided with an upwardly-directed pivot-pin c^2 , on which is placed

a cup-shaped support d , the bottom of which is raised or conical in form, as shown at d^2 , and provided with a central opening d^3 , through which the pivot-pin c^2 passes, and passed through the top of said pivot-pin above 55 the bottom of the cup-shaped support d is a key-pin d^4 .

Secured to the top of the cup-shaped support d is a telescopic chute e , and in practice the cup-shaped support d is preferably made 6 circular in form, and the upper or main section of the chute is bolted to the perimeter thereof, as shown at e^2 , and the opposite sides of the upper or main section of the chute are provided with inwardly-curved flanges e^3 , 65 which form keepers to hold the supplemental or outer or lower section e^2 of said chute.

Secured to the rear end and bottom portion of the body α^2 of the cart or wagon is a stationary shield g , composed of metal and covered so as to inclose the usual opening h , formed in the rear end of the body portion of the cart or wagon or in the tail-gate, and this opening is closed by a vertically-movable slide-door h^2 in the usual manner, said door 70 being operated by a lever h^4 , pivoted to the end of the body of the cart or wagon, as shown at h^5 , and connected with the door h^2 by a link h^6 . The shield g is intended to prevent the coal from scattering as it falls from 75 the body of the cart or wagon in the usual manner and drops into the chute f .

In the form of construction shown the telescopic chute e is composed of two parts, and the support d thereof is adapted to slide freely 80 on the beam b^2 , and the part e^2 of said chute is adapted to be extended when the parts are 85 in the position shown in Figs. 2 and 3 transversely of the pavement, so as to discharge the coal into a coal-hole i .

In Fig. 1 I have shown at j a portion of a street and at j^2 a part of a pavement adjacent thereto, and the coal-hole i is in said pavement, and in practice the cart or wagon is drawn up adjacent to the pavement or sidewalk, as shown in Fig. 1, and the chute e in the keepers e^3 is extended, as shown in said figure. The door h^2 is then raised, and the coal is discharged through the opening g into the telescopic chute e and slides there- 90 95 100

through into the coal-hole *i*. By supporting the part *d* in the manner shown and described it is adapted to tilt, as shown in Figs. 1 and 3, and also free to turn horizontally, and by means of this construction the discharge of the coal from the cart or wagon is facilitated, as said coal may be discharged laterally or directly to the rear or in any desired manner.

In practice I prefer to form the support of the telescopic chute *e* so that it cannot be removed from its support *b*² and is always in position for use and when not discharging coal the separate parts of the chute *e* are telescoped and the support *d* thereof slid under the body of the cart or wagon, and in order to accomplish this result I provide the beam *b*² with an upwardly-directed lip *k* at its outer end, which prevents the withdrawal of the chute-holder from said beam in the operation of drawing out said chute-holder and extending the parts of the chute. In the form of construction shown the pivot-pin *c*² bears on the bottom of the main part of the chute and the support *d*, and the chutes are thus supported on the pin *c*² and free to turn thereon horizontally and also to tilt laterally.

By making the part *c* movable on the supplemental support *b*² longitudinally of the bed or body *a*² the adjustment of the telescopic chute *e* with reference to the opening *h* is facilitated, and the parts may be adjusted so that the coal will always be discharged into the telescopic chute, no matter in what position the telescopic chute may be, and the slide *c* may be adjusted, together with the support *d*, along the supplemental support or bar *b*² to any desired point.

Although I have described my improvement as applicable to coal carts or wagons, it will be apparent that the same may be applied for the purpose of discharging various other articles from a cart, wagon, or various other receptacles, and various changes in and modifications of the construction described may be made without departing from the spirit of my invention or sacrificing its advantages.

Having fully described my invention, what I claim as new, and desire to secure by Letters Patent, is—

1. A chute-support for coal and other wag-

ons, comprising a horizontal hanger supported beneath the bed or body of the wagon and parallel therewith and longitudinally thereof, a slide mounted thereon and adapted to move longitudinally thereof, a support connected with said slide and adapted to turn horizontally and to swing in a vertical plane thereon, and a telescopic chute one end of which is secured to said support, substantially as shown and described.

2. A chute-support for coal and other wagons, comprising a horizontal hanger supported beneath the bed or body of the wagon and parallel therewith and longitudinally thereof, a slide mounted thereon and adapted to move longitudinally thereof, a support connected with said slide and adapted to turn horizontally and to swing in a vertical plane thereon, and a telescopic chute one end of which is secured to said support, the bed or body of the wagon being also provided in the rear end thereof with a door and with a shield inclosing said door and through which the coal passes into said chute, substantially as shown and described.

3. A chute-support for coal and other wagons, comprising a horizontal hanger supported beneath the bed or body of the wagon and parallel therewith, a slide mounted thereon and provided with an upright member, a cup-shaped support mounted on said member and through the bottom of which said member passes, and a telescopic chute secured to said support, substantially as shown and described.

4. A chute-support for coal and other wagons, comprising a horizontal hanger supported beneath the bed or body of the wagon and parallel therewith, a slide mounted thereon and provided with an upwardly-directed pin and a chute-support pivoted on said pin, said chute-support being adapted to swing in a horizontal plane and to tilt laterally on said pin, substantially as shown and described.

In testimony that I claim the foregoing as my invention I have signed my name, in presence of the subscribing witnesses, this 18th day of March, 1904.

JOHN GIBSON.
